[57] CLAIM

The ornamental design for a glove holder and shape retainer, as shown and described.

DESCRIPTION

FIG. 1 is a perspective view of a glove holder and shape retainer showing my new design;

FIG. 2 is a right side elevational view thereof, the opposite side being a mirror image;

FIG. 3 is a front elevational view thereof;

FIG. 4 is a rear elevational view thereof;

FIG. 5 is a top plan view thereof; and,

FIG. 6 is a bottom plan view thereof.

Undisclosed and partially disclosed surfaces are plain and unornamented.
